(57) **CLAIM**

The ornamental design for a dressing table, as shown and described.

DESCRIPTION

FIG. 1 is a frontal downward toward the right perspective view of the dressing table according to my design;
FIG. 2 is a frontal elevational view thereof;
FIG. 3 is a left elevational view thereof, a right elevational view thereof being a mirror image of FIG. 3;
FIG. 4 is a top plan view thereof;
FIG. 5 is a rear elevational view thereof; and,
FIG. 6 is a frontal downward towards the right perspective view thereof with a removable portion shown removed for completeness of illustration.
